UNITED STATES PATENT OFFICE.

JOHN S. ORAM, OF CLEVELAND, OHIO.

WINDLASS.

933,781.

Specification of Letters Patent. Patented Sept. 14, 1909.

Application filed July 20, 1908. Serial No. 444,495.

To all whom it may concern:

Be it known that I, JOHN S. ORAM, a citizen of the United States of America, residing at Cleveland, in the county of Cuyahoga and State of Ohio, have invented certain new and useful Improvements in Windlasses; and I hereby declare the following to be a full, clear, and exact description of the invention, such as will enable others skilled in the art to which it pertains to make and use the same.

This invention relates to improvements in windlasses more especially designed for the bending into the proper shape to form a barrel of a set of staves which are widest centrally between and gradually reduced in width toward their ends and assembled on end and placed tightly together within a hoop placed upon the floor.

20 The primary object of this invention is to provide a windlass of the character indicated whereby the staves are quickly and properly bent into the shape required to form the barrel.

25 Another object is to provide a windlass comprising a winding drum and a guide-sheave which is arranged laterally of the drum and engaged by a chain or cable which is operatively attached at one end to the drum and extends to and over the sheave and employed in controlling the size of the loop formed by a rope or flexible band which is arranged between the sheave and the drum and has one end-portion thereof attached to the other end of the said chain or cable, said loop-forming member having its other end-portion crossing the first-mentioned end-portion of the loop-forming member and attached to another chain or cable which is operatively connected with the drum and employed in controlling the size of the afore-said loop and both chains or cables being arranged to be simultaneously wound on or paid out by the drum according as the drum

45 is rotated in the one or the other direction and operatively connected with means acting to unwind the chains or cables from the drum so that the drum, as soon as it is rendered free to rotate in the direction required to pay out the chains or cables upon winding up the chains or cables to form the barrel, is rotated to pay out the chains or cables by the pull upon the chains or cables by the said cable-unwinding means and thereby to loosen

the loop-forming member relative to the 55 barrel.

Another object is to provide simple and reliable means acting to actuate and thereby draw both ends of the loop-forming member toward each other to loosen the loop relative to the barrel and thereby to permit of the removal of the loop-forming member from the upper end of the barrel after a hoop has been placed around the set of staves at the said end of the barrel.

With these objects in view, and to the end of realizing other advantages hereinafter appearing, this invention consists of certain features of construction, and combinations of parts, hereinafter described, pointed out 70 in the claims, and illustrated in the accompanying drawings.

In the said drawings, Figure 1 is a side elevation of a windlass embodying my invention. Fig. 2 is a top plan of the windlass, and portions are broken away and in section in this figure. Fig. 3 is a vertical section on line 3—3, Fig. 1, looking in the direction indicated by the arrow. Fig. 4 is a side elevation corresponding with Fig. 1, except that in Fig. 4 the staves are shown bent into the shape required to form a barrel and a hoop is shown encircling the upper end of the barrel to hold the staves in their bent form.

My improved windlass comprises a horizontally arranged rectangular or oblong bed-plate A which is mounted on and suitably secured to legs a under the ends of the bed-plate and resting on the floor m as shown in Figs. 1 and 4. A winding drum D is arranged horizontally over and transversely of one end-portion of the bed-plate A and operatively mounted on a correspondingly arranged shaft d. The shaft d has bearing 90 in two boxes e and e arranged at opposite ends respectively of the drum and supported from the bed-plate A.

On the shaft d between one of the boxes e and the adjacent extremity of the shaft is loosely mounted a gear G which is slidable endwise of the shaft and meshes with a pinion P operatively mounted on a suitably supported shaft p which is arranged horizontally below and parallel with the shaft d. The shaft p is operatively provided at its rear end with a driving pulley p' to which power is applied by a suitably driven belt p'. 105

A friction-clutch for controlling operative connection between the gear G and the shaft d is provided (see Fig. 2). One member 6 of this clutch is formed on the gear at the inner end of the gear, and the other member 7 of the clutch is operatively mounted on the shaft next the outer end of the adjacent box e. Obviously therefore a shifting of the gear G inwardly toward the winding drum 10 establishes operative connection between the companion members 6 and 7 of the clutch and thereby operatively connects the said gear with the drum and consequently the latter with the shaft p, and it will be observed therefore that the said gear, to interrupt operative connection between the drum and the shaft p is shifted outwardly.

The gear G is provided at its outer end with a hub g which has an annular peripheral groove g' engaged by a lever I for shifting the gear, which lever is suitably supported from the adjacent leg a, being preferably fulcrumed at its lower end, as at I', horizontally and at a right angle to the shafts d and p, to a bracket a' rigid with the said leg, as shown in Figs. 1 and 4. Of course the pinion P is long enough to be in mesh with the gear G in either position of the gear.

30 As already indicated, the drum D is arranged over one end-portion of the bed-plate A. A guide-sheave J is placed with its axis vertically over the other end-portion of the said bed-plate. The sheave J is supported 35 from the bed-plate in any approved manner.

A rope or flexible band or member K is arranged between the sheave J and the drum D and is preferably in the form of a loop and has its end-portions crossing each other 40 and projecting toward the drum D and sheave J respectively. That end of the loop-forming member K which projects toward the sheave J is operatively attached to one end of a chain or cable L which leads 45 from the loop-forming member to and over the sheave and thence to and is operatively connected with the drum, and the other end of the loop-forming member is operatively attached to a chain or cable Q which leads 50 from the loop-forming member to and is operatively connected with the drum.

The loop-forming member K is arranged to encircle a set of staves s which are placed in an upright position on the floor m within 55 a hoop h which rests on the floor and are tightly fitted together at their side edges within the said hoop to form one end of the barrel to be formed. The staves are widest centrally between and gradually reduced in 60 width toward their ends. Another hoop h' encircles the set of staves at a distance above the floor equal to about one-third of the height of the barrel to be formed, which hoop is temporarily used to prevent falling 65 apart of the staves preparatory to the sur-

rounding of the set of staves at the upper end of the staves by the loop-forming member K.

The gear G is rotated in the direction indicated by the arrow placed thereon in Figs. 1 and 4, and, upon shifting the said gear inwardly to establish operative connection between the companion members 6 and 7 of the clutch, the drum D is rotated in the said direction and thereby winds up the connected chains or cables L and Q, and the winding up of the said chains or cables actuates opposite ends of the loop-forming member K toward the sheave J and drum D respectively and thereby reduces the size of the loop 80 formed by the said loop-forming member and bends the staves into the shape required to form the barrel, and when the staves have been bent inwardly at their upper ends far enough another hoop h² is placed around the 85 upper end of the barrel being formed, as shown in Fig. 4.

A ratchet-wheel T is operatively mounted on the shaft b and engaged by a pawl t which is pivotally supported from a bracket a² rigid with the bed-plate A, and the arrangement of the parts is such that the said pawl and ratchet-wheel coöperate in preventing a return movement of the drum D during the application of the hoop h to the 95 barrel upon arresting the rotation of the drum in the direction required to wind up the engaging chains or cables, but, of course, the said pawl is disengaged from the ratchet-wheel preparatory to the loosening of the 100 loop-forming member K relative to the barrel, and obviously the said loop-forming member immediately upon the application of the hoop h² to the barrel is loosened relative to the barrel to permit its removal upwardly from the upper end of the barrel upon rendering the clutch inoperative and thereby permitting the rotation of the drum in the direction required to pay out the 105 connected chains or cables L and Q. 110

The bed-plate A is provided between the sheave J and drum D, and preferably between the ends of the loop-forming member K and consequently between adjacent ends of the chains or cables L and Q with a slot 115 8 which extends vertically through and is arranged longitudinally of the bed-plate. Two sheaves 10 and 12 which are placed with their axes horizontally and parallelly are arranged within opposite end-portions 120 respectively of the slot 8 and suitably supported from the bed-plate.

A stationary bar R is arranged below the bed-plate A and has its central portion 13 arranged horizontally and longitudinally of the slot 8 and below the sheaves 10 and 12. The bar R has opposite end-portions 14 thereof diverging downwardly from the central portion 13 of the bar toward the legs a at opposite ends respectively of the bed- 130

plate. Each end-portion 14 of the bar R forms a guide for a weight w which has a vertical slot 15 through which the said guide extends and is provided with two suitably supported horizontally arranged parallel rollers 16 arranged transversely of the said slot and spaced longitudinally of the guide.

Two chains or cables 17 and 18 lead between and over the sheaves 10 and 12 respectively and are attached to the weights w. The chain 17 leads from the connected weight to and over the sheave 10 and thence to the chain or cable L with which it is operatively connected preferably substantially at the point of connection between the said chain or cable L and the loop-forming member K. The chain or cable 18 leads from the connected weight to and over the sheave 12 and thence toward the chain or cable Q with which it is operatively connected preferably substantially at the point of the connection between the said chain or cable Q and the loop-forming member K.

It will be observed that the weights w act to pull the adjacent ends of the chains or cables L and Q toward each other and consequently act to rotate the drum in the direction required to pay out the said chains or cables and to loosen the loop-forming member relative to the upper end of the barrel formed by the said loop-forming member. Obviously therefore when the upper end of the barrel has been formed by the winding of the chains or cables L and Q upon the drum and a hoop h² has been placed around the upper end of the barrel, as shown in Fig. 4, the operative connection between the drum and the gear G is interrupted and the pawl t disengaged from the ratchet-wheel T to permit the said drum to rotate in the direction required to pay out the connected chains or cables, and obviously the drum when it has thus been rendered free to pay out the connected chains or cables will be rotated by the action of the weights w in the direction required to pay out the connected chains or cables and thereby loosen the loop-forming member relative to the barrel to the extent required to permit the said loop-forming member to be removed upwardly from the barrel. I would also remark that during the bending of the upper portions of the staves inwardly by the operation of the loop-forming member K the barrel being formed may, in any approved manner, be held or prevented from tipping.

What I claim is:—

1. A windlass comprising a flexible member forming a loop and having its end-ports arranged to move across each other, two cables operatively connected with opposite end-ports respectively of the loop-forming member, means for simultaneously operating the said cables to reduce the size of the loop, and means acting to draw the

loop-connecting ends of the cables toward each other.

2. A windlass comprising a suitably supported winding drum, a suitably guided cable operatively engaging at one end with the drum, a flexible loop-forming member having an end-portion thereof attached to the other end of the said cable and arranged to move across the other end-portion of the loop-forming member, another cable attached at one end to the last-mentioned end-portion of the loop-forming member and operatively engaging at its other end with the drum, means for rotating the drum in the direction required to wind up the cables, and means acting to draw the loop-connecting ends of both cables toward each other, and both cables being arranged to be simultaneously wound on or paid out by the drum as the case may be.

3. A windlass comprising a winding drum, a guide-sheave spaced a suitable distance from the drum; a cable operatively engaging at one end with the drum and extending to and over the guide-sheave, a loop-forming member arranged between the guide-sheave and the drum and having one end-portion thereof attached to the other end of the said cable, and crossing the other end-portion of the loop-forming member; another cable attached at one end to the last-mentioned end-portion of the loop-forming member and operatively engaging at its other end with the drum, and means acting to draw the loop-connecting ends of both cables toward each other.

4. A windlass comprising a suitably supported winding drum; a suitably guided cable operatively attached at one end to the drum; a flexible loop-forming member having one end-portion thereof attached to the other end of the said cable, said loop-forming member having its other end-portion arranged to move across the first-mentioned end-portion of the loop-forming member; another cable attached at one end to the second-mentioned end-portion of the loop-forming member and operatively attached at its other end to the drum; means for rotating the drum in the direction required to wind up the cables, and suitably applied weights acting to draw the loop-connecting ends of both chains toward each other, and both cables being arranged to be wound on or paid out by the drum as the case may be.

5. A windlass comprising a flexible member forming a loop and having its end-ports arranged to move across each other, two chains operatively connected with opposite ends respectively of the loop-forming member, means for simultaneously operating the chains to decrease the size of the loop; downwardly diverging guides below the ends of the loop-forming member, weights resting on and movable along the guide, two

guide-sheaves between the ends of the loop-forming member; cables operatively connected with the ends of the loop-forming member and leading over the guide-sheaves 5 toward and being connected with the weights.

6. A windlass comprising an oblong bed-plate provided between its ends with a slot extending vertically through and arranged longitudinally of the bed-plate; a suitably 10 supported winding drum arranged above and transversely of the bed-plate at one end of the bed-plate; a guide-sheave arranged above the bed-plate at the other end of the bed-plate; a chain operatively attached at 15 one end to the drum and extending to and over the sheave; a loop-forming member arranged between the sheave and the drum and having one end-portion thereof attached to the other end of the said chain, said loop-forming 20 member having its other end-portion crossing the first-mentioned end-portion of the loop-forming member; another chain attached at one end to the second-mentioned end-portion of the loop-forming member and 25 operatively attached at its other end to the drum; means for rotating the drum in the direction required to wind up the chains; two guide-sheaves arranged within opposite 30 end-portions respectively of the aforesaid slot and placed with their axes transversely of the slot; downwardly diverging guides below the last-mentioned sheaves; weights having rollers resting on and arranged transversely of the said guides, and cables attached to the weights, 35 thence leading to and between and over the said last-mentioned sheaves and operatively

connected with the loop-connecting ends of the aforesaid chains.

7. A windlass comprising a suitably supported winding drum; a suitably guided chain operatively attached at one end to the drum; a loop-forming member having one end-portion thereof attached to the other end of the said chain, said loop-forming member having its other end-portion arranged to move across the first-mentioned end-portion of the loop-forming member; another chain attached at one end to the second-mentioned end-portion of the loop-forming member and operatively attached at its other end to the drum; means for rotating the drum in the direction required to wind up the chains; two suitably supported guide-sheaves arranged adjacent the loop-connecting ends of the chains; a stationary bar having a central portion arranged below the sheaves and downwardly diverging end-portions; weights resting on and movable endwise of the end-portions of the said bar, and cables attached to the weights, thence leading to and between and over the sheaves and thence leading toward and operatively connected with the aforesaid chains, and both chains being arranged to be simultaneously wound on or paid out by the drum according as the drum is rotated in the one or the other direction.

In testimony whereof, I sign the foregoing specification, in the presence of two witnesses.

JOHN S. ORAM.
